UNITED STATES PATENT OFFICE.

EMIL DEISTER, OF FORT WAYNE, INDIANA, ASSIGNOR TO DEISTER MACHINE COMPANY,
OF FORT WAYNE, INDIANA, A CORPORATION OF INDIANA.

CONCENTRATING APPARATUS.

1,334,524.

Specification of Letters Patent. Patented Mar. 23, 1920.

Application filed April 21, 1917. Serial No. 163,609.

To all whom it may concern:

Be it known that I, EMIL DEISTER, residing at Fort Wayne, in the county of Allen and State of Indiana, a citizen of the 5 United States, have invented or discovered certain new and useful Improvements in Concentrating Apparatus, of which improvements the following is a specification.

When pulp is fed onto a table and flows 10 by reason of the inclination of the table, toward its lower or tailings discharge, the heavier particles or values settle down onto the surface of the table, so that there is present on the table a lower stratum or layer 15 consisting of the values, an upper stratum consisting of sand containing a minimum amount of values, and an intermediate stratum consisting of sand and a very considerable percentage of values. Were it not 20 for the presence of riffles, these strata would flow together toward the tailings discharge edge. The purpose of the riffles is to stop the flow of values toward the tailings discharge edge and divert their direction of 25 flow toward the mineral discharge edge without checking or diverting the normal flow of the sand stratum, out of which the values have settled. Hence it is the practice to make the riffles of a height greater 30 than the thickness of the lower stratum but not sufficiently high as to extend into the upper stratum which is free from values. As these upper and lower strata merge one 35 into the other, a percentage of values will pass over the riffles, and a very considerable percentage of sand will be caught by the riffles, and will move with the values toward the mineral discharge edge. While in efficiently operating tables, a maximum of the 40 minerals or values will reach the mineral discharge edge, the movement of the sand, caught by the riffles from the line of separation, toward the middlings discharge edge, will have mixed therewith a considerable 45 percentage of minerals and hence the middlings will be undesirably high in minerals.

It is well known that a nearly perfect separation of the values from the sand can be effected on a table having low and closely 50 arranged riffles, such as are formed by cutting shallow grooves or fine corrugations in the surfaces of the tables, the depths of the grooves being substantially equal to the thickness of the lower or values stratum.

On a table having such low closely arranged 55 riffles not only the upper or sand stratum, but also the intermediate stratum of mixed sand and values will flow over the riffles without retardation or diversion, but the values will settle into the shallow grooves and 60 move along them to the mineral discharge edge. It is also characteristic of the operation of tables having low riffles or corrugations, that there will be less agitation of the pulp, and hence there will be a more rapid 65 and complete gravity segregation of the values.

The invention described herein has for its object the utilization of riffles of sufficient height to permit of the maintenance of a 70 constant line of separation and of low closely adjacent riffles or corrugations for the segregation of values passing over the main riffles with the sand. The invention is hereinafter more fully described and 75 claimed.

In the accompanying drawings forming a part of this specification, Figure 1 is a top plan view of what is known as the Deister duplex plateau table having the invention 80 described herein applied thereto; Fig. 2 is a top plan view of another type of table embodying the improvement; Figs. 3 to 9 inclusive are sectional detail views showing on an enlarged scale forms or embodiments 85 of the invention forming the subject matter claimed herein; Fig. 10 is similar to Fig. 2, but showing in connection therewith a Deister plateau; Fig. 11 is a sectional view on a plane indicated by the line XI—XI, 90 Fig. 10; Fig. 12 shows another method of applying the improved riffle to a table, the ends of the riffles being bent toward the feed side; Fig. 13 shows the improved riffle applied to a table in such manner as to intersect the line of movement of the table; Fig. 95 14 is a view similar to Fig. 13 but showing in addition the Deister plateau, and Fig. 15 is a cross section on line XV—XV, Fig. 14.

While the improvement claimed herein is 100 shown in connection with a Deister single or double plateau and several other types of concentrating tables, it will be understood that the improvement can be applied to any other form, shape or construction of 105 table.

In the practice of the invention, the main riffles 1 are arranged in any suitable man-

- ner or at any desired angle to the line of flow of material from the point of feed toward the tailings discharge edge, or to the line of movement of the table. Generally, 5 these riffles are made of a height, equal or approximately equal to the normal and average depth of the stratum formed by minerals which have settled out of the pulp, but as the depth of this stratum will depend 10 very largely on the richness or leanness of the material treated, the height of the riffles will vary considerably. And further, these main riffles which are adapted to divert the direction of movement of the values toward 15 the mineral discharge edge of the table and also to establish and maintain the line of separation constant as hereinbefore described, may be of uniform height throughout their entire length or such height may vary. 20 These major riffles are made of sufficient width on top to permit of the formation thereon of corrugations consisting at least of two ridges and an intermediate groove or valley, but from this minimum, the main 25 riffles may be made of any desired width. It is preferred, however, to construct the main riffles 1 so that there will be a plurality of small auxiliary corrugations on top of each main riffle. The main riffles may be 30 constructed in any suitable manner as, for example, by strips of wood, metal, rubber, or glass fastened to the table, or by cutting away portions of the table intermediate the desired positions of the main riffles, and the 35 small or auxiliary corrugations 2 may be formed on the top of these main riffles, by cutting the grooves in the surfaces of these main riffles, by securing narrow strips on the tops of the main riffles, by attaching cap 40 strips of glass, metal, wood, rubber, linoleum, or any other suitable material having their upper faces suitably corrugated on the tops of strips attached to or integral with the main deck or cover of the table. The 45 cross sectional contour of these auxiliary corrugations may be of any desired shape *i. e.*, inverted V's, V's with concave sides, rectangular, or in the form of truncated cones, as shown in the several views.
- 50 In applying the main riffles having corrugations or auxiliary riffles formed on their surfaces, as described, to the deck of a table they may be arranged with the ends toward the mineral discharge edge on a diagonal 55 line as in the tables shown in Figs. 2, 12 and 13, or the discharge ends of the main riffles may terminate on an inclined surface as shown in Figs. 10, 11, 14 and 15, or at any desired point beyond the same as in 60 the Deister table shown in Fig. 1, or any other suitable means known in the art, may be employed for determining and maintaining a constant line of separation of the sand and minerals.
- 65 As the main riffles are of a height equal

to or not materially greater than the depth of the stratum of values in contact with the table, comparatively little sand will be caught and diverted by these main riffles, and the material flowing over the main 70 riffles will contain quite a relatively large percentage of values. But in passing across the corrugated surfaces of the main riffles, more or less of these values will settle down into the fine grooves or valleys intermediate 75 the small ridges, and, due to the vibration of the table, will move along the same and be discharged from such grooves or valleys at the ends of the main riffles.

It is characteristic of a table having the 80 improved riffles, that as the percentage of sand caught and diverted by the main riffles is reduced to a minimum, and as very little sand will be caught and carried along with the values by the corrugations or auxiliary 85 riffles, the percentage of sand delivered at the line of final separation of the values and sand, is small and the percentage of values which is discharged over the middlings discharge edge, will also be reduced 90 to a minimum.

As hereinbefore stated, the table with which my invention is incorporated may be formed of the usual or any desired shape or contour. In Fig. 1 is shown what is known 95 as the Deister duplex plateau table, which is provided, adjacent to the mineral discharge edge, with one or more plateaus 3, the approaches to which are inclined as at 4. The main riffles 1 are arranged as shown and described in Letters Patent No. 1,088,685, dated March 3rd, 1914, and may extend to the apex of the first incline 4 or to that of the second incline, and in some cases entirely 100 across the plateau, the rear end of which forms the mineral discharge edge of the table. These riffles are preferably formed substantially wider than those heretofore employed and are provided on their upper surfaces with corrugations 2. It will be understood that the invention described herein 105 is not limited as regards the width of the main riffles, nor of their spacing along the table, but it is generally preferred to so space the main riffles that the channels between adjacent riffles will be less than the width of the main riffles themselves.

In the type of table shown in Fig. 2, the main riffles increase in length from the upper to the lower edge of the table, so that their 120 discharge ends will be on a diagonal line, along or adjacent to which the final separation of the values and the sand occurs. The width and spacing of the main riffles on this type of table will vary with the character of 125 the material treated. In Fig. 10, the improved riffle is shown applied to a table having a plateau 11 with an inclined approach 12, as described and claimed in Letters Patent No. 1,040,164, granted October 1, 1912 to 135

E. and W. F. Deister, and No. 1,209,943, granted December 26, 1916, to Emil Deister. The portions of the riffles on this incline should be tapered corresponding approximately to the degree of slope of the incline 5 to the degree of slope of the incline 12. In the construction shown in Figs. 10 and 11, as well as the constructions shown in other figures, it may be advisable in case of highly mineralized ore, to extend shallow 10 riffles either part way or all the way across the washing surface, as shown and described in the patents above referred to.

As will be seen by reference to Figs. 3 to 9 inclusive, the riffles may be constructed in a variety of ways and the corrugating or riffling of the upper surfaces effected either by forming ridges and intermediate grooves in the surface of the riffles, or by securing to the top of the riffles a strip of suitable material having its upper surface corrugated. In Fig. 3, the main riffle 1 is shown as formed of wood and having V-shaped grooves cut in its upper surface. The corrugations consisting of ridges and intermediate grooves thus formed on the upper surfaces of the major riffles may be of any desired shape in cross section and of any desired size, *i. e.*, with a considerable depth and width of grooves as shown in Fig. 3, or 25 with a shallow and narrow groove as shown in Fig. 4. The major riffles may be formed of metal strips 1 as shown in Fig. 5, or of strips of glass as shown in Fig. 6. The corrugations on the tops of these main riffles 30 may be fine and relatively low or the ridges and intervening grooves may be angular in cross section and of considerable width, as shown in Fig. 6. If desired, strips 5 of linoleum or rubber may be employed as main 35 riffles, the upper surfaces being corrugated, as shown in Fig. 7. The desired height of the main riffling may be attained by inserting a strip 6 between the linoleum forming the surface of the table and the strip 5 forming the riffle, as stated, or if preferred, the main riffle may be made solid, as shown at 40 7 in Fig. 8 and its upper surface, which is formed with grooves and alternating ridges 45 may be made convex.

50 Another form which is desirable consists in making the main portion of the riffle of a strip 8 of suitable material and providing a cap 9 therefor, which may be made of wood, metal, glass, linoleum or rubber, or 55 any other suitable material, said cap having its surface corrugated in any suitable manner.

In most cases, it will be preferred to cover the deck of the table with linoleum as at 60 10, as is the usual practice, but such covering is not necessary in the practice of the invention described herein, and further if desired, the surface of the table itself whether formed of wood, linoleum, rubber or other 65 material, may be provided with fine corrugations as shown in Fig. 9, substantially in the same manner as practised in corrugating the upper surface of the main riffles.

As the channels intermediate the major riffles on a table will divert not only the minerals but also the sand caught between these riffles and mingled with the stratum of minerals, the larger the total area of the channels, the larger the percentage of sand carried toward the mineral discharge edge. 70 And further, it has been found that when the ore is coarse, it will respond more quickly to the differential vibrations of the table, and will move so quickly along the channels that efficient washing out of sand can- 75 not be effected unless the table is given an excessive transverse inclination. It will be understood that by making the main riffles wider the channel areas are proportionally decreased, and by making the main riffles 80 lower and at the same time providing them with means for receiving values from the material passing over them, concentration of the coarse ores can be effected without adjusting the table to an excessive transverse 85 inclination.

Fig. 12 shows a construction in which portions of the improved riffles are arranged parallel with the direction of vibration of the table, and the portions 13 of the riffles 95 adjacent to the cleaning up surface 14 are inclined to the direction of motion for the purpose of facilitating the final separation of the sand and values. In some cases, it may be desirable to arrange the entire riffle 100 at an angle to the direction of vibration, as shown in Figs. 13 and 14, and to combine such angular arrangement of riffles with a plateau 11, having an inclined approach 12 as shown in Figs. 14 and 15. 105

I claim herein as my invention:

1. A reciprocating table having a concentrating surface and adapted to transport concentrates to the discharge edge thereof, said table being inclined for gravitational flow 110 transverse of the direction of travel of concentrates, riffles on said surface in spaced relation and extending in the direction of concentrate travel, the tops of said riffles being substantially parallel with the table surface 115 in the direction of gravitational flow and each of said tops being provided with a plurality of longitudinal ridges and grooves substantially narrower and shallower than the channels between the riffles. 120

2. A reciprocating table having a concentrating surface and adapted to transport concentrates to the discharge edge thereof, said table being inclined for gravitational flow 125 transverse of the direction of travel of concentrates, said table having alternating channels and riffles extending in the direction of travel of concentrates, the tops of said riffles being substantially parallel to the general plane of the table, each of said riffles 130

being provided with a plurality of longitudinal ridges and grooves substantially narrower than the channels between the riffles.

3. A reciprocating table having a concentrating surface and adapted to transport concentrates to the discharge edge thereof, said table being inclined for gravitational flow transverse of the direction of travel of concentrates, riffles on said surface in spaced relation and extending in the direction of concentrates travel, the tops of said riffles being substantially parallel with the table surface in the direction of gravitational flow and each of said tops being provided with a plurality of longitudinal ridges and grooves substantially narrower and shallower than the channels between the riffles.

4. A reciprocating table having a concentrating surface and adapted to transport concentrates to the discharge edge thereof, said table being inclined for gravitational flow

transverse of the direction of travel of concentrates, riffles on said surface in spaced relation and extending in the direction of concentrates travel, the tops of said riffles being substantially parallel with the table surface in the direction of gravitational flow and each of said tops being provided with a plurality of longitudinal ridges and grooves substantially narrower and shallower than the channels between the riffles, in combination with an upwardly inclined surface arranged along a diagonal line relative to the line of movement of the table, said inclined surface being co-extensive with the line of separation between the mineral and gangue.

In testimony whereof I have hereunto set my hand.

EMIL DEISTER.
